UNITED STATES PATENT OFFICE

WILLIAM H. GIBBS, OF MILWAUKEE, WISCONSIN

HAMMER

Application filed December 6, 1926. Serial No. 152,819.

This invention relates to hammers, and more particularly to a hammer having removable tips or striking members.

The present invention is intended more particularly as an improvement over the hammer disclosed in my Patent No. 1,532,135, issued to me April 7, 1925. While the hammer of my patent identified has proved to be very satisfactory in many respects, there are some 10 objections thereto which are overcome by the hammer of the present application. In the patented hammer, I have found by extensive experience, that the handle formed of metal tubing is objectionable as it does not 15 have the desired give or resiliency with the result that in using the hammer the user's arm and hand is subjected to undesirable jars and strains. I have also found that it is desirable to provide means for insuring the 20 tight seating of the heads of the tip members against the ends of the body of the hammer, preventing injury to these members and insuring greater accuracy in use of the hammer.

One of the main objects of my invention is to provide a hammer of simple and inexpensive construction which will avoid the objections above noted in connection with the patented hammer, which objections also apply to other hammers of this type at present in use. A further object is to provide simple and efficient means for securing the tip members to the body of the hammer and for drawing them tightly against the ends of the body, 25 this means also serving to effectually secure the handle to the body. Another object is to provide simple and efficient means whereby the handle is secured to the body in such manner as to eliminate all looseness or play, 30 this means being particularly adapted for receiving and securing the end portion of a wooden hammer handle of standard construction. Further objects will appear from the detail description.

In the drawings:—

Figure 1 is a perspective view of the hammer;

Figure 2 is a central transverse sectional view taken substantially on line 2—2 of Figure 1;

Figure 3 is a section taken substantially on line 3—3 of Figure 2, the tip members and securing screw being shown in elevation;

Figure 4 is a section taken substantially on line 4—4 of Figure 3; and

Figure 5 is a detail of one of the tip members.

The hammer includes a body of substantially barrel shape, this body being formed of two complementary sections 1 and 2. 60 Each section is provided at the central portion of its inner face with a transversely extending recess 3, this recess extending from one lateral edge of the section to within a short distance of the other edge thereof. These 65 two recesses form a socket for reception of the end portion 4^a of a wooden handle 4 of known construction. Each of the sections is further provided with an inwardly projecting point or spur 5 disposed to enter into 70 the wood of portion 4^a of handle 4. These spurs are disposed adjacent the outer end of the handle receiving socket and remote from a securing screw 6 which passes thru portion 4^a of the handle 4 and has threaded 75 engagement with body section 2. This screw is provided with an enlarged head 7 which fits within a recess 8 provided in section 1, the head being transversely slotted at 9 for reception of the blade of a screw driver or 80 other suitable tool. Preferably, a spring washer 10 is confined between head 7 and the inner end of recess 8 and serves to hold the screw 6 against reverse rotation due to jars or vibration incident to the use of the hammer. The screw 6 serves to force the sections 1 and 2 toward each other into tight 85 clamping engagement about the handle and to simultaneously force the spurs 5 into the handle, this screw also acting as an anchoring member to positively prevent withdrawal 90 of the handle from the body.

This hammer is intended for use in machine shops and other establishments where a hammer provided with relatively soft striking members is desired. I have illustrated the hammer as provided with a striking or tip member 11 of lead at one end and a tip member 12 of rubber at the other end, though it is 100 to be understood that these tip members can

be made of any suitable or preferred material. The tip members are of similar construction and each includes a head 13 of frusto-conical shape from the center of the base of which extends a reduced shank or neck 14 provided at the end thereof remote from head 13 with an annular flange 15, the outer surface of which is beveled or inclined at 16 from the periphery of the flange to neck 14.

10 Each section of the body is provided with an approximately semi-cylindrical recess 17 extending from its outer end centrally thereof. At its inner end this main recess communicates with a supplemental recess 18 of 15 greater radius, the outer wall of which is inclined at 19 outwardly of the section toward the main recess 17. This shoulder 19 contacts with the beveled surface or shoulder 16 of flange 15. It will be noted that the supplemental recess 18 is of greater width than flange 15. In assembling the hammer, section 2 is placed upon a suitable support with its inner or recessed surface directed upwardly and the tip members and handle are then 20 placed in position with portion 4^a of the handle 4 and the shanks or necks 14 of the tip members disposed loosely in the recesses of section 2. Section 1 is then placed in position over section 2 fitting loosely about the 25 upper portions of the necks of the tip members and portion 4^a of the handle, after which screw 6 is inserted through section 1 and the handle and is threaded into section 2. As the screw is turned into its innermost position it forces the sections of the hammer body 30 toward each other, and the shoulders 19, due to their inclination, contact with shoulders 16 of the shanks 14 and draw the tip members inwardly so as to dispose the bases of these 35 members in close contact with the ends of the hammer body. Continued movement of the sections towards each other serves to tightly 40 clamp the necks 14 of the tip members between the body sections and to tightly secure the handle in the body in the manner previously 45 set forth. As the tip members are drawn tightly against the ends of the body all possibility of looseness or play of these members is eliminated, which insures greater accuracy 50 and ease in the use of the hammer and effectually prevents damage to the tip members such as results where undue looseness or play of these members is permitted. In this respect the means for drawing the tip members into 55 tight contact with the ends of the hammer body is of great importance and, so far as I am aware, is broadly new. It is also to be noted that the means for drawing the tip members into contact with the hammer body 60 and securing them therein also serves to secure the handle in the body and anchor it against withdrawal. This renders it possible to quickly and easily disassemble and reassemble the hammer for replacement of tip members, which is an important consideration,

producing a hammer of very simple and highly efficient construction.

I am aware that hammers of this general type having detachable tip members have been proposed, but such hammers are generally objectionable in that they are of rather complicated construction and do not provide satisfactory means whereby a handle of wood or other suitable resilient material may be employed. A further objection to hammers of this kind with which I am familiar is that no means is provided whereby the tip members are caused to be drawn tightly against the ends of the hammer body, the result being that in such hammers the tip members have a certain amount of undesirable play or looseness which seriously interferes with use of the hammer. I do not, therefore, intend to claim broadly the construction of a hammer of this general character except in so far as this construction of hammer cooperates with the means above described for accomplishing the desired results set forth.

What I claim is:—

1. In a hammer of the character described, a body formed of two complementary sections having recesses extending from their ends forming terminal sockets, tip members having elements extending into the sockets to be clamped between said sections, a handle, and a securing member extending through the sections and the handle and securing the same together, said member acting to force the sections of the body toward each other. 90

2. In a hammer of the character described, a body formed of two complementary sections provided in their inner faces with central transverse recesses forming a handle receiving socket, a handle extending into said socket, tip members having elements clamped between the end portions of the body sections, and a securing screw passing through one of the body sections and the handle and having threaded engagement with the other body section for forcing said sections toward each other. 100

3. In a hammer of the character described, a body formed of two complementary sections provided with central transverse recesses forming a handle receiving socket and with spur elements projecting from the inner faces of the recesses, a wooden handle extending into said socket, tip members having elements clamped between the end portions of the body sections, and a securing screw passing through one of the body sections and the handle and having threaded engagement with the other body section for forcing said sections toward each other. 115

In witness whereof, I hereunto subscribe my name this 24th day of November, 1926.

WILLIAM H. GIBBS.
